US00D892088S

(12) **United States Design Patent** (10) **Patent No.:** **US D892,088 S**
(45) **Date of Patent:** **** Aug. 4, 2020**

(54) **EARPIECE STABILIZER**

(71) Applicant: **New Audio LLC**, New York, NY (US)

(72) Inventors: **Drew Stone Briggs**, Brooklyn, NY (US); **Nicholas Slaney**, Jersey City, NJ (US); **Thomas C. Wilson**, Brooklyn, NY (US); **Marten Wallby**, Malmo (SE)

(73) Assignee: **New Audio LLC**, New York, NY (US)

(**) Term: **15 Years**

(21) Appl. No.: **29/715,971**

(22) Filed: **Dec. 5, 2019**

(57) **CLAIM**

The ornamental design for an earpiece stabilizer, as shown and described.

DESCRIPTION

FIG. 1 is a top, front perspective view of an earpiece stabilizer showing our new design.

FIG. 2 is a right side elevational view thereof.

FIG. 3 is a left side elevational view thereof.

FIG. 4 is a front elevational view thereof.

FIG. 5 is a back elevational view thereof.

FIG. 6 is a top plan view thereof; and,

FIG. 7 is a bottom plan view thereof.

The broken lines in the drawings depict portions of the earpiece stabilizer that form no part of the claimed design.

1 Claim, 2 Drawing Sheets
